UNITED STATES PATENT OFFICE.

ALEXANDER W. KINTER, OF DAYTON, PENNSYLVANIA.

COMMODE.

No. 829,160.

Specification of Letters Patent.

Patented Aug. 21, 1906.

Application filed November 25, 1905. Serial No. 289,081.

To all whom it may concern:

Be it known that I, ALEXANDER W. KINTER, a citizen of the United States, residing at Dayton, in the county of Armstrong and 5 State of Pennsylvania, have invented a new and useful Commode, of which the following is a specification.

This invention relates to commodes, and has for its object to provide a simple, inexpensive, and efficient device of this character in 10 which the seat and cover are detachable, so that the same may be readily removed to facilitate the cleaning of the commode.

A further object of the invention is to provide means for supporting the cover of the 15 seat in open position and means for preventing the escape of fetid odors arising from the contents of the commode.

With these and other objects in view the 20 invention consists in the construction and novel combination and arrangement of parts hereinafter fully described, illustrated in the accompanying drawings, and pointed out in the claims hereto appended, it being understood 25 that various changes in form, proportions, and minor details of construction may be resorted to without departing from the principle or sacrificing any of the advantages of this invention.

30 In the accompanying drawings, forming a part of this specification, Figure 1 is a top plan view of a commode constructed in accordance with my invention. Fig. 2 is a side elevation of the same, showing in dotted lines 35 the cover of the seat supported in open position. Fig. 3 is a longitudinal sectional view of a portion of the commode shown in Fig. 2.

Similar numerals of reference indicate corresponding parts in all the figures of the drawings.

40 The improved device consists of portable vessel or receptacle 5, having a rigid handle 6 and provided with a pivoted bail 7 for convenience in transporting the vessel from 45 place to place.

Supported on the upper edge of the receptacle 5 is a seat 8, having the usual opening 9, and secured to said seat is a metal collar or casing 10, provided with an annular shoulder 50 11, defining a depending flange 12, which engages the interior walls of the receptacle and serves to prevent accidental displacement of said seat. The seat 8 is provided with a pivoted cover 13, having an annular groove 14 55 formed therein for the reception of a gasket 15 to prevent the escape of fetid odors when

the lid is closed, there being a similar gasket 16 interposed between the upper edge of the receptacle and the shoulder 11, as shown.

Secured to the stationary handle 6 is a lug 60 or projection 17, adapted to engage the pivoted end of the cover 13 and limit the opening movement of the latter. Fastened to the top of the cover in any suitable manner, as by screws 17', is a plate 18, the free 65 end of which is bifurcated to form a pair of downwardly-curved spring-arms 19, which embrace the handle 6 when the cover is open and engage a wear-plate 20, preferably formed by extending the shoulder 11 laterally at the 70 reduced end of the seat, as shown. The spring-arms 19 serve as an additional means for supporting the cover in open position when the seat is in position on the receptacle and also serve to support said cover independently of the lug or projection 17 when the seat is detached or removed from the receptacle. The cover 13 is provided with a suitable finger-piece or knob 21 for convenience 75 in elevating the cover, and said cover is preferably provided with a reinforcing-strip 22 to give additional strength to the same. By having the seat detachable the latter may be quickly removed when it is desired to empty 80 the contents of the receptacle, while the lug 85 or projections support the cover in position for use as a back to the commode. Attention is also called to the fact that when the cover is in open position the spring-arms by engagement with the stationary handle serve to 90 prevent rotation of the seat.

From the foregoing description it will be seen that there is provided an extremely simple and efficient device admirably adapted for the attainment of the ends in view.

95 Having thus described the invention, what is claimed is—

1. In a device of the class described, a receptacle having a stationary handle, a seat supported by the receptacle and having an opening formed therein and communicating with the receptacle, a cover pivoted to the seat for normally closing said opening, and spaced arms carried by the cover and having their free ends curved downwardly and 100 adapted to embrace the handle and bear against the seat for supporting the cover in open position.

105 2. In a device of the class described, a receptacle having a stationary and movable handle, a lug secured to the stationary handle, a seat supported by the receptacle and

having an opening formed therein and communicating with the receptacle, and a cover pivoted to the seat for normally closing the opening, said cover being supported in open position by engagement with the lug.

3. In a device of the class described, a receptacle, provided with a lug or projection, a seat supported by the receptacle and having an opening formed therein and communicating with the receptacle, a cover pivoted to the seat and held in open position by engagement with the lug, and a pair of spring-arms secured to the cover and adapted to engage the seat to assist in supporting the cover in open position.

4. In a device of the class described, a receptacle having a stationary handle, a seat supported by the receptacle and having an opening formed therein communicating with the receptacle, a depending flange secured to the seat for engagement with the interior walls of the receptacle and defining an annular shoulder, a lug secured to the handle, a cover pivoted to the seat and held in open position by engagement with said lug, a pair of spring-arms carried by the cover and adapted to embrace the lug and bear against the seat for limiting the opening movement of said seat, a gasket secured to the cover for engagement with the seat, and a gasket interposed between the annular shoulder and the receptacle.

5. In a device of the class described, a re-

ceptacle having a stationary handle provided with a vertically-disposed lug, a seat supported by the receptacle and having an opening formed therein and communicating with the receptacle, a depending flange secured to the seat for engagement with the interior walls of the receptacle and defining an annular shoulder a portion of which is extended laterally at the rear of the seat to form a wear-plate, and a pair of arms secured to the pivoted end of the cover and adapted to embrace the lug and bear against the wear-plate for limiting the opening movement of the cover.

6. In a device of the class described, a receptacle provided with a handle, a seat supported by the receptacle and having an opening formed therein and communicating with the receptacle, a cover pivoted to the seat for normally closing said opening, and a pair of spaced arms secured to the pivoted end of the cover and adapted to engage the seat for limiting the opening movement of the cover, said arms being adapted to embrace the handle when the cover is in open position.

In testimony that I claim the foregoing as my own I have hereto affixed my signature in the presence of two witnesses.

ALEXANDER W. KINTER.
